P. M. RAINY,
TELEGRAPH SYSTEM,
APPLICATION FILED APR. 22, 1915.

1,245,507.

Patented Nov. 6, 1917.

UNITED STATES PATENT OFFICE.

PAUL M. RAINY, OF GLEN RIDGE, NEW JERSEY, ASSIGNOR, BY MESNE ASSIGNMENTS,
TO WESTERN ELECTRIC COMPANY, INCORPORATED, A CORPORATION OF NEW YORK.

TELEGRAPH SYSTEM.

1,245,507.

Specification of Letters Patent.

Patented Nov. 6, 1917.

Application filed April 22, 1915. Serial No. 23,049.

To all whom it may concern:

Be it known that I, PAUL M. RAINY, a citizen of the United States, residing at Glen Ridge, in the county of Essex and State 5 of New Jersey, have invented certain new and useful Improvements in Telegraph Systems, of which the following is a full, clear, concise, and exact description.

This invention relates to telegraph systems, and its principal object is to provide 10 a simple arrangement for the relaying or retransmission of current impulses.

In operating telegraph systems on the well-known Baudot multiplex principle, it 15 has been recognized for some time that it is possible to send messages from one station to another through an intermediate station without the necessity for any manual manipulation at the intermediate point, and 20 without interfering with other messages between the intermediate station and either terminal station over the same transmission lines. This method of operation, often aptly designated as forking or extending, is clearly 25 described in H. W. Pendry's "*The Baudot Printing Telegraph System*," and the principal object of this invention is to improve the system and apparatus therein disclosed. This invention may, however, be advan- 30 tageously employed, where desired, in simply relaying the impulses from one section of line to another, and while it is particularly adapted for use in multiplex operation, it is clearly not limited to this field.

For the accomplishment of the above ends, 35 the invention contemplates a system of relays and connections interposed between sections or branches of a transmission line, whereby each current impulse received may 40 act upon a particular unit of the system, which unit controls the character of the corresponding impulse in the next section or branch, besides bringing about a circuit condition which maintains the units in their 45 altered condition until a train of impulses representing a cycle of operations is completed.

The above and other objects of this invention will be fully set forth in the following 50 description and claims and will be more readily understood by reference to the accompanying drawing wherein the preferred embodiment is shown diagrammatically.

A transmission line section 5 interconnects

one distant station with an intermediate or 55 retransmitting station A, while another section 6 interconnects the intermediate station with another distant station. The apparatus at the two distant stations is not shown since it may be of any desired type. 60

At the intermediate station A, the current impulses in section 5 traverse a relay 10 whose armature is connected to a grounded source of energy 11. The active front contact of relay 10 is joined to the rotating arm 12 of a suitable receiving current distributor 13. This distributor may be composed of any number of groups of contacts, each group comprising a plurality of insulated segments such as 15, 16, 17, 18 and 70 19, in the drawing four such groups being shown. Only the group associated with the retransmission of signals, however, is shown connected, the other groups being preferably associated with printing apparatus to 75 convert the proper impulses in section 5 into printed characters.

Segments 15 to 19 inclusive are each connected to one of the terminals of the windings of a group of relays 25, 26, 27, 28 and 80 29 respectively, the other terminals of which are connected to a back contact of a clear-out relay 31. Each relay 25 to 29 inclusive is provided with two armatures 32 and 33. Armatures 32 coöperate with back and front 85 contacts, respectively connected to the positive and negative poles of a divided and grounded source of energy 34 and are connected to corresponding insulated segments 85, 36, 37, 38 and 39 of a transmitting current distributor 40. Armatures 33 of relays 25 to 29 coöperate with front contacts associated with the windings of the respective relays and are all connected to a grounded source of energy 41. It is thus apparent that 90 95 when any of the relays 25 to 29 inclusive are energized their armatures 33 complete holding circuits therefor through the armature of the clear-out relay 31.

Distributor 40 is provided with a rotating arm 45 adapted to successively connect segments 35 to 39 inclusive to line section 6. There may be other groups of segments similar to segments 35 to 39 (in the drawing three other such groups being shown), which 105 may be used for intercommunication between station A and the distant station on section 6.

Arm 45 of distributor 40 also carries a pair of brushes 46 insulated therefrom and adapted to interconnect a segment 47 which is joined to the winding of clear-out relay 5 31 and a segment 48 which is connected to a grounded source of energy 49.

In the specific embodiment shown in the drawing, arms 12 and 45 are joined to and rotated by the same shaft 50 which is driven 10 by any suitable source of power in the direction of the arrow. This source is so regulated by any of the well-known means that the arm 12 rotates in the proper phase relation to a corresponding distributor, preferably of a similar construction, located at 15 a sending station on line 5, and arm 45 rotates in the proper phase relation to a corresponding, and preferably similar distributor, at a receiving station on line 6. 20 Arms 12 and 45 need not pass over corresponding segments in corresponding groups simultaneously, it merely being necessary that the selected relays 25 to 29 have sufficient time to operate before the brush on 25 arm 45 leaves the respectively corresponding segments 35 to 39. Preferably arm 12 may lead arm 45 slightly, as shown in the drawing.

Assuming that relay 10 is polarized so 30 that its armature engages the active contact only when the positive impulses arrive over section 5, the operation of the system is as follows:

If the first impulse of a particular combination is of positive polarity, relay 10 causes its armature to complete a circuit from source 11, arm 12, segment 15, relay 25 and back contact and armature of relay 31 to ground. Relay 25 thereupon becomes 35 energized, attracting its armatures 32 and 33 against their respective front contacts. Armature 32 connects the positive pole of the grounded source 34 to segment 35 and when arm 45 of distributor 40 reaches this 40 segment the pole is joined to section 6. Armature 33 completes a holding circuit including grounded source 41, relay 25, and the back contact and armature of relay 31. Relay 25 is therefore locked in a condition 45 50 to connect the positive pole of source 34 with segment 35.

Assuming the second impulse in section 5 to be negative, relay 10 breaks the circuit including its armature and active contact 55 and while arms 12 and 45 are respectively associated with segments 16 and 36, relay 26 remains unenergized and the negative pole of source 34 is connected through back contact and armature 32 of relay 26, segment 60 36 and arm 45 to section 6. This action continues throughout the cycle of operations consisting of five impulses, whenever an impulse in section 5 is positive, the positive pole of source 34 being connected by the corresponding relay 25 to 29 inclusive with the

proper segment 35 to 39 inclusive of distributor 40. When, however, any impulse is negative, the corresponding relay 25 to 29 inclusive remains unenergized and the negative pole of source 34 is connected to 70 the proper segment 35 to 39 inclusive. Upon brushes 46 interconnecting segments 47 and 48, which event occurs after segment 39 has been associated with section 6, a circuit is completed from source 49 through clear-out relay 31. Clear-out relay 31, thereupon pulling up its armature, opens the holding circuits for the relays 25 to 29 which have been previously energized and the relaying apparatus is again in a condition to retransmit another set of impulses. 75 80

It is therefore readily apparent that the current impulses in section 5 associated with the group of segments connected to relay 25 to 29 inclusive are relayed or retransmitted 85 to section 6. The impulses therefore associated with this group of segments may be relayed on through the intermediate station A to a distant station on section 6 without the necessity of any supervisory or manual 90 operation at the intermediate station. On the other hand, the apparatus associated with the other three groups of segments of distributors 13 and 40 may be utilized for 95 intercommunication between instruments associated with these groups and co-operating apparatus associated with corresponding groups of like distributors at the distant station on sections 5 and 6 without in any way interfering with the through transmission 100 between such distant stations. If desired, relays 25 to 29 may be caused to control any desired form of local selecting apparatus as a printer or perforator. 105

While the distributors 13 and 40 have 110 been referred to in the above description as receiving and transmitting distributors, respectively, it is to be understood that this term relates merely to the function of those groups of segments of these pieces of apparatus while working in connection with the relaying of message impulses between the sections of the through transmission line. Each distributor so far as segments in the other quadrants are concerned, may act as either a transmitting or receiving distributor, and when the system is properly duplexed, may operate as a sending and transmitting distributor, simultaneously. 115 120

What is claimed is:

1. A telegraph system comprising a line divided into sections; and a relaying apparatus interposed between adjacent sections thereof including a plurality of relays variably selectable by impulses received from one 125 of the sections, a source of energy for forming impulses for the next section, circuit connections therefor controlled by said relays, and holding circuits for said relays closed thereby in response to the impulses received. 130

2. A telegraph system for relaying signal current impulses comprising a telegraph line divided into sections; and a relaying apparatus interposed between adjacent sections 5 including a current distributer associated with one section, a plurality of relays coöperating therewith to be selectively acted upon by a plurality of current impulses, holding circuits for said relays, a source of 10 relaying current, a current distributer interposed between said source and another section of said line, and circuit connections whereby said relays control the coöperation of said source and said second mentioned 15 distributer and complete the holding circuits for themselves in accordance with the

current impulses in the first mentioned section.

3. A retransmitting apparatus comprising a receiving current distributer, a plurality 20 of relays adapted to be selectively actuated by current impulses associated therewith, a transmitting current distributer, a source of current adapted to coöperate with said transmitting distributer the coöperation being controlled by said relays, holding circuits for and controlled by said relays, and means for discontinuing the action of said circuits.

In witness whereof, I hereunto subscribe 30 my name this 21st day of April A. D., 1915.

PAUL M. RAINES.
